UNITED STATES PATENT OFFICE

2,099,561

ELECTRIC VALVE CONVERTING APPARATUS

Rolland C. Griffith and Burnice D. Bedford, Schenectady, N. Y., assignors to General Electric Company, a corporation of New York

Application November 25, 1933, Serial No. 699,758
Renewed June 12, 1937

7 Claims. (Cl. 175—363)

Our invention relates to electric valve converting apparatus and more particularly to such apparatus of the vapor electric type and to arrangements for controlling the operation of the apparatus in response to the occurrence of reverse arcs within the apparatus.

It is a well known fact that the vapor electric apparatus in operation are subject to reverse arcs which may be occasioned by any of a number of disturbing operating conditions. These reverse arcs generally appear as arcs between the several anodes of a multi-anode vapor electric apparatus; or as a reverse arc from the cathode to the anode of a single-anode vapor electric apparatus operating in a system utilizing a number of such apparatus. If such reverse arcs within the vapor electric apparatus are allowed to persist they may cause serious damage, not only to the apparatus itself, but to the system and other apparatus with which the vapor electric apparatus is associated. It has heretofore been proposed to control the operation of such vapor electric apparatus of the metal tank type by providing the anodes of the apparatus with associated control grids and controlling the potential of these grids in response to the reversal of the potential between the cathode and the metal tank, which, it has been discovered, is an indication of an actual or incipient reverse arc. This arrangement as previously devised, however, has not been directly applicable to a system employing a plurality of vapor electric apparatus with independent cathode potentials. Our present invention, while of a general application, is primarily directed to such a system employing a plurality of single anode vapor electric apparatus with independent cathode potentials.

It is an object of our invention, therefore, to provide an improved vapor electric valve converting system in which the operation of the apparatus will be controlled in response to the occurrence of actual or incipient reverse arcs within the apparatus.

It is another object of our invention to provide an improved vapor electric valve converting system in which the control electrodes associated with the several anodes of the converting apparatus are normally excited with a control potential to control the conductivity of the apparatus and in which this controlling potential is suppressed in response to the occurrence of incipient or actual reverse arcs within the apparatus.

In accordance with one embodiment of our invention, the several anodes of a vapor electric ap-

paratus of a valve converting system are provided with associated control electrodes upon which are impressed control potentials for normally controlling the conductivity of the apparatus. Also enclosed within the separate container of each vapor electric apparatus is an auxiliary conductive electrode, or member, in contact with the ionized vapor. In the case of an apparatus with a metallic container, this member may comprise the container itself. This conductive member is connected to its respective cathode through a unilaterally conductive device and an insulating transformer. The secondary windings of the several insulating transformers are connected to the common control circuit of an auxiliary electric valve which is connected to modify the magnetization, as for example, by saturation, of the main control transformer. In this manner, the occurrence of a reverse arc within any of the vapor electric apparatus reverses the potential between its auxiliary conductive member and its cathode, sending an impulse of current through its associated transformer which is effective to render conductive the auxiliary electric valve to saturate the main control transformer and thus to remove the excitation and render the main valve converting apparatus nonconductive.

For a better understanding of our invention, together with other and further objects thereof, reference is had to the following description taken in connection with the accompanying drawing, and its scope will be pointed out in the appended claims. The single figure of the drawing is a diagrammatic representation of our invention as applied to the protection from reverse arcs of a vapor electric valve converting system for transmitting energy from a three phase alternating current supply circuit to a direct current load circuit.

Referring now more particularly to the drawing, there is shown a vapor electric valve converting system embodying our invention for transmitting energy from a three phase alternating current supply circuit 10 to a direct current load circuit 11. This apparatus includes a transformer provided with a primary network 12 connected to the supply circuit 10 and a secondary network 13 provided with an electrical neutral connected to one side of the direct current circuit 11. The phase terminals of the network 13 are connected to the other side of the direct current circuit 11 through vapor electric valves 14, 15 and 16. A current smoothing reactor 17 is preferably included in the direct current circuit. The electric valves 14, 15 and 16 are each pro-

vided with an anode, a cathode, a control grid, and an auxiliary conductive member or electrode 18 in contact with the ionized vapor of the valve, although, as stated above, in case the valve is 5 contained within a metallic envelope, the envelope itself may constitute the auxiliary conductive member. The control electrodes of the electric valves 14, 15 and 16 are connected to their common cathode circuit through protective 10 resistors 19, negative bias batteries 20, and the secondary windings of the main control transformers 21, 22 and 23, respectively. The main control transformers 21-23, inc., may be of any desired type, although we prefer to use self-saturating transformers, so that the potentials induced in the secondary windings are of peaked 15 wave form. The primary windings of these transformers are energized from the appropriate phases of the supply circuit 10 through any suitable phase adjusting mechanism, such as a rotary phase shifting transformer 24.

In order to render ineffective the normal excitation circuit for the control electrodes of the several electric valves under reverse arc conditions, the auxiliary conductive members 18 of the 25 electric valves 14-15-16 are connected to their respective cathodes through unilaterally conductive devices, such as contact rectifiers 25-26-27 and the primary windings of auxiliary control 30 transformers 28-29-30, respectively. The secondary windings of the transformers 28-29-30 are connected in parallel through protective resistors 31 and to the control electrode of an auxiliary electric valve 32. This common control 35 circuit may include also a biasing battery 33, if desired. Each of the main control transformers 21-22-23 is provided with an auxiliary saturating winding 34, and these windings are connected to be excited in series from a source of 40 current, such as a battery 35, through the auxiliary electric valve 32. Switching means shown as a manually operated switch 36 may be provided to interrupt the current in the saturating windings 34 and restore the operation of the system.

The general principles of operation of the above described rectifying system will be well understood by those skilled in the art, so that a detailed description is believed to be unnecessary. It will also be well understood that the average 45 energy supplied to the load circuit 11 may be controlled by adjusting the rotary phase shifting transformer 24 to adjust the phase relationship between the alternating potentials impressed upon the control electrodes of the electric valves 14-15-16 and the anode potentials of these 50 valves. If it be assumed, for example, that at any particular instant the electric valve 15 is operating normally as a rectifying valve, and electric valve 14 fails, so that a reverse arc tends to 55 flow from its cathode to its anode, it will be seen that two of the phases of the network 13 tend to become short circuited through the electric valves 15 and 14 in series. As stated above, it has been demonstrated that under such conditions, the potential of the auxiliary conductive 60 electrode 18 with respect to the cathode of the electrode valve 14 reverses in potential from a normally positive value to a negative value. This reversal may take place upon the occurrence of 65 an incipient arc back which may actually never develop into a power arc. The unilaterally conductive devices 25-26-27 are so connected that, with normal potential impressed upon the auxiliary electrodes 18, no current flows in the primary 70 windings of the auxiliary control trans-

formers 28-29-30. Upon the reversal of potential between the electrode 18 of the valve 14 and its cathode, however, a current impulse is sent through the primary winding of the transformer 28 which impresses a positive impulse on the auxiliary electric valve 32 to render this valve conductive. In this manner, the source of current 5 35 is effective to energize the saturating windings 34 of the main control transformers 21-22-23 to completely suppress the potentials normally 10 induced in the secondary windings of these transformers. The result is, that the negative bias batteries 20 in the control circuits of the electric valves 14-15-16 are effective to render these 15 valves nonconductive. Valve 32 is preferably of the vapor electric discharge type so that it will maintain the transformers 21-22-23 in a saturated condition until the circuit of their saturating windings is opened by the switch 36. In this way an incipient or actual reverse arc in any of 20 the several electric valves 14-15-16 is effective to interrupt the operation of the system and thus prevent damage to the system and its associated apparatus.

While we have described what we at present 25 consider the preferred embodiment of our invention, it will be obvious to those skilled in the art that various changes and modifications may be made without departing from our invention, and we, therefore, aim in the appended claims to cover 30 all such changes and modifications as fall within the true spirit and scope of our invention.

What we claim as new and desire to secure by Letters Patent of the United States, is:

1. In combination with a vapor electric valve 35 converting apparatus comprising an anode, a cathode, a control electrode, and a conductive member in contact with the ionized vapor of the apparatus, a saturable control transformer for exciting said control electrode to control the 40 energy transmitted by said apparatus, and means responsive to the potential between said conductive member and said cathode for varying the saturation of said transformer to control the energy transmitted by said apparatus. 45

2. In combination with a vapor electric valve 50 converting apparatus comprising an anode, a cathode, a control electrode, and a conductive member in contact with the ionized vapor of the apparatus, a saturable control transformer for exciting said control electrode to control the energy transmitted by said apparatus, and means responsive to a reversal of the potential between 55 said conductive member and said cathode for saturating said control transformer to suppress the excitation to said control electrode and to render said valve apparatus nonconductive.

3. In combination with a vapor electric valve 60 converting apparatus comprising an anode, a cathode, a control electrode, and a conductive member in contact with the ionized vapor of the apparatus, an excitation circuit for said control electrode including a source of negative bias potential, a self saturating transformer provided with a winding included in said control circuit to 65 impress upon said control electrode an alternating potential of peaked wave form for normally controlling the conductivity of said apparatus, and means responsive to a reversal of the potential between said conductive member and said cathode upon the occurrence of a reverse arc in 70 said apparatus for saturating said transformer to suppress the excitation to said control electrode and to render said apparatus nonconductive.

4. In combination with a vapor electric valve 75

converting apparatus comprising an anode, a cathode, a control electrode, and a conductive member in contact with the ionized vapor of the apparatus, a control transformer for exciting said control electrode to control the energy transmitted by said apparatus, a saturating winding for said transformer, means including an auxiliary electric valve for controlling energization of said saturating winding, and means responsive to the potential between said conductive member and said cathode for controlling the conductivity of said auxiliary valve.

5. In combination with a vapor electric valve converting apparatus comprising an anode, a cathode, a control electrode, and a conductive member in contact with the ionized vapor of the apparatus, a control transformer for exciting said control electrode to control the energy transmitted by said apparatus, a saturating winding for said transformer, an energizing circuit for said saturating winding including an auxiliary electric valve, and means responsive to a reversal of potential between said conductive member and said cathode upon the occurrence of a reverse arc 20 in said apparatus for rendering conductive said auxiliary electric valve, whereby said vapor electric apparatus is rendered nonconductive.

6. In an electric valve converting system, a plurality of electric valves each provided with an anode, a cathode, a control electrode, and a con-

ductive member in contact with the ionized vapor of the apparatus, control transformer apparatus connected to excite the control electrodes of said valves to normally control their conductivity, an auxiliary control circuit interconnecting the conductive member and the cathode of each of said valves, and a circuit for saturating said control apparatus including an auxiliary electric valve, said auxiliary electric valve being connected to respond to the reversal of potential in any of said 10 control circuits. 5

7. In an electric valve converting system, a plurality of electric valves each provided with an anode, a cathode, a control electrode, and a conductive member in contact with the ionized vapor of the apparatus, an exciting circuit for the control electrode of each of said valves, each including a saturable transformer for normally controlling the conductivity of its associated valve, an auxiliary control circuit interconnecting the 20 conductive member and the cathode of each of said valves including a unilaterally conductive device, and a circuit for saturating said transformers including an auxiliary electric valve, said auxiliary electric valve being connected to be excited by the flow of current in any of said auxiliary control circuits. 25
